UNITED STATES PATENT OFFICE.

JOHN LEWIS WETTLAUFER, OF TORONTO, ONTARIO, CANADA.

FEEDING APPARATUS FOR CONCRETE-MIXING MACHINES.

1,030,361.

Specification of Letters Patent.

Patented June 25, 1912.

Application filed May 19, 1910. Serial No. 562,148.

To all whom it may concern:

Be it known that I, JOHN LEWIS WETTLAUFER, of the city of Toronto, in the county of York, in the Province of Ontario, Canada, have invented certain new and useful Improvements in Feeding Apparatus for Concrete-Mixing Machines, of which the following is the specification.

My invention relates to improvements in feeding apparatus for concrete mixing machines, and the object of the invention is to devise an apparatus of this class, whereby an ordinary wheel barrow may be utilized to dump into the lift hopper of the apparatus and the material raised with ease and with an expenditure of a minimum amount of power and discharged into the mixing machine.

A further object is to economize time by enabling the feeding apparatus being filled while the material is being mixed in the mixing machine.

Another object is to dispense with the erection of temporary scaffolding in order to feed the mixing machine.

Another object is to devise such an apparatus as may be readily adapted to mixing machines of different types.

Another object is to make the apparatus simple and compact.

To effect these objects my invention consists of a lift hopper supported on runways and a frame secured to the truck of the mixing machine, and a suitable elevating apparatus therefor, the parts being arranged and constructed in detail as herein-after explained.

Figure 1, is a side elevation of my improved feeding apparatus. Fig. 2, is a side elevation of the truck showing the feeding apparatus in end elevation.

In the drawings like letters of reference indicate corresponding parts in each figure.

A is the truck and B is a mixing drum suitably supported on the truck.

C is the feeding chute, which extends into the open end B' of the feeding drum.

D D are standards secured at one side of the truck A at desired distances apart opposite the end of the feeding drum and maintained rigid in the upright position by bracing rods D'. The uprights are made of angle iron and are connected together at the front near the top by a cross angle iron D².

D³ is a cross shaft journaled in suitable

bearings at the top of the standard D and carrying a grooved wheel D⁴.

E is the main driving shaft of the mixer, which is journaled in suitable bearings E' and is designed to rotate the mixer in a manner, which it is not necessary to describe. The shaft E is provided with a gear wheel E², which meshes with the gear wheel E³ on the counter shaft E⁴. A clutch E⁵ is also located on the counter shaft, the moving member of such clutch being operated by a forked lever E⁶.

E⁷ is the winding drum, which remains stationary or turns according as to whether the clutch is thrown in or out. The clutch 70 is of the usual form or type and need not here be described.

F is a diagonally set cross bar secured at the back of the bars D and carrying the grooved wheels G and G'.

H H are struts, which are pivotally connected at one end to bearings H' at the top of the truck at one side. The opposite ends of the struts H H normally rest on the ground.

I I are supplemental struts, which are pivotally connected to the standards D D. The struts I rest normally on grooved rollers I' journaled in pins I² in the struts H H. The inner ends of the struts I extend upwardly 80 to a point on a level with the bottom of the chute C.

J is the hopper, which is of a scoop-shape being open at the inner end and closed at the outer end. The hopper J is supported on 90 grooved rollers J' at the inner end, which ride on the struts I.

K are toggle-jointed bars pivotally connected to the front or lower end of the hopper when in the normal position at one end 95 and to the strut H at the opposite end.

L is a grooved wheel, which is held to rotate on the cross shaft L' having bent ends L² secured to the sides of the hopper J.

M is the winding rope, which is connected 100 to the cross bar D² at the top of the standards D D and passes around the wheel F and up over the wheel D⁴ down around the guiding wheels G and G' thence around the winding drum E⁷. By throwing in the 105 clutch E⁵ the winding drum has motion imparted to it and pulls on the rope M, thereby first drawing the hopper J upwardly toward the standards along the struts I, thus bringing the weight closer to the point 110

where the power is applied and reducing the leverage, so that when the hopper is being raised up it will be raised up most advantageously and in raising the hopper and parts connected thereto will assume the position shown in dotted lines in Fig. 1, with the mouth of the hopper above the feeding chute. Of course when the hopper is being raised to this position the weight is being gradually lightened as the material is being dumped into the chute C and mixing drum. When the hopper is in the lowermost position an ordinary wheel barrow can be wheeled up to it and dumped into it and thus the erection of supplemental scaffolding now frequently employed in connection with mixing machines to produce means for feeding the drum is entirely dispensed with.

By the construction, which I have adopted, I am enabled to raise the load from the ground with the expenditure of a minimum amount of power.

What I claim as my invention is—

1. In a mixing machine or the like carried on a suitable support, a feeding apparatus comprising standards suitably supported, struts supported near the bottom of the standard, a feeding hopper supported on the struts, a cross shaft secured at the front end of the hopper and wheel on the cross shaft, a cross bar extending between the standards, a rope connected to the cross bar and extending around the pulley on the cross shaft of the hopper, a grooved wheel suitably journaled at the top of the standards and over which the rope extends, and guiding pulleys located behind the standards, a winding drum and clutch located on a shaft journaled in suitable bearings and around which winding drum the rope extends as and for the purpose specified.

2. In a mixing machine or the like carried on a suitable support, feeding chute and truck, the combination with the standards and a lower strut pivoted at the top in proximity to the standards, grooved wheels journaled on pins in the lower strut, upper struts pivotally connected to the standards and resting on the grooved wheels, of a hopper having grooved wheels resting on the upper strut, means for supporting the hopper at the front and means connected to the front of the hopper and extending over the top of the standard for simultaneously moving the hopper longitudinally

on the struts and raising it as and for the purpose specified.

3. In a mixing machine or the like carried on a suitable support, feeding chute and truck, the combination with the standards and a lower strut pivoted at the top in proximity to the standards, grooved wheels journaled on pins in the lower strut, upper struts pivotally connected to the standards and resting on the grooved wheels, of a hopper having grooved wheels resting on the upper strut, toggle jointed bars pivotally connected to the front of the hopper and to the lowermost struts, and means connected to the front of the hopper and extending over the top of the standard for simultaneously moving the hopper longitudinally on the struts and raising it as and for the purpose specified.

4. In a mixing machine or the like carried on a suitable support, feeding chute and truck, the combination with the standards and a lower strut pivoted at the top in proximity to the standards, grooved wheels journaled on pins in the lower strut, upper struts pivotally connected to the standards and resting on the grooved wheels, of a hopper having grooved wheels resting on the upper strut, toggle jointed bars pivotally connected to the front of the hopper and to the lowermost struts, a rope connected to the top of the standard and passing over suitable guiding wheels on the hopper and on the top of the standard for simultaneously moving the hopper, longitudinally toward the feeding opening and raising it as and for the purpose specified.

5. A feeding apparatus for mixing machines comprising struts designed to form run ways extending from the ground to the feeding opening, a hopper supported on the run ways, toggle-jointed bars connecting the hopper to the struts and means for raising the hopper as and for the purpose specified.

6. In a feeding apparatus of the class described, a hopper and struts forming runways therefor and means for raising the struts and hopper simultaneously during the period that the hopper is passing along the run ways as and for the purpose specified.

JOHN LEWIS WETTLAUFER.
